COMBINED CIGARETTE DISPENSER AND LIGHTER

Paul Rizek, Chicago, Ill.

Application June 1, 1953, Serial No. 25,280

Term of patent 3½ years

(Cl. D85—2)

To all whom it may concern:

Be it known that I, Paul Rizek, a citizen of the United States of America, residing at Chicago, in the county of Cook and State of Illinois, have invented a new, original, and ornamental Design for a Combined Cigarette Dispenser and Lighter, of which the following is a specification, reference being had to the accompanying drawing, forming part thereof.

In the drawing:

Fig. 1 is a front elevational view of a combined cigarette dispenser and lighter, showing my new design;

Fig. 2 is a side elevational view thereof;

Fig. 3 is a top plan view thereof; and

Fig. 4 is a cross-sectional view thereof, taken along line 4—4 in Fig. 1, looking in the direction of the arrows.

The broken line showing of a cigarette in Fig. 1 is for illustrative purposes only. The figures are diagonally lined to indicate transparency.

I claim:

The ornamental design for a combined cigarette dispenser and lighter, as shown and described.
